UNITED STATES PATENT OFFICE.

JOHN F. NEAL AND DOREL NEAL, OF KOKOMO, INDIANA.

APPARATUS FOR LOCATING SUNKEN VESSELS.

1,178,094.

Specification of Letters Patent.

Patented Apr. 4, 1916.

Application filed November 5, 1915. Serial No. 59,854.

To all whom it may concern:

Be it known that we, JOHN F. NEAL and DOREL NEAL, citizens of the United States, residing at Kokomo, in the county of Howard, State of Indiana, have invented a new and useful Apparatus for Locating Sunken Vessels, of which the following is a specification.

The present invention is an appliance for attachment to a submarine vessel or other ship, whereby should the vessel sink for any reason whatever, one or more floats or buoys can be liberated to rise to the surface of the water for signaling to other vessels, the location of the sunken vessel, and the floats or buoys serving to lift into place means for the guidance and attachment of grapnels in order that the vessel may be salvaged. This provides means whereby the vessel can be readily located if it has sunk, and whereby the vessel can be raised. In case of a submarine vessel, if the vessel has not been submerged too long, the crew can also be saved by the prompt location and salvaging of the vessel.

It is also within the scope of the invention to provide an apparatus of the nature indicated which is comparatively simple, compact and inexpensive in construction, which can be readily applied to submarine and other vessels, and which will serve its office in a thoroughly practical, reliable and efficient manner.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawings, wherein:

Figure 1 is an elevation of a sunken submarine vessel, parts being broken away and shown in section, and one of the floats or buoys being liberated. Fig. 2 is a perspective view of a sunken submarine vessel turned over on one side with both floats or buoys liberated. Fig. 3 is an enlarged section detail of one of the improved devices with the float or buoy in normal position. Fig. 4 is an enlarged sectional detail of

the coupling for connecting the two cables of each float, and providing means for the engagement of a grapnel, whereby the vessel can be raised.

In the drawings, the invention is illustrated as being applied to a submarine vessel, although it is to be understood at the outset that the apparatus may be applied to various ships.

The submarine illustrated is supplied with a pair of the improved devices, one fore and one aft of the conning tower, although it is to be understood that any number of the devices may be employed as may be deemed expedient.

In carrying out the invention, the shell or deck 1 of the vessel is provided with a circular opening 2 for each of the devices, and a tapered or frusto-conical receptacle 3 has its larger open end provided with an out-turned annular flange or rim 4 riveted or otherwise secured to the under surface of the shell 1 around the opening 2, so that the receptacle 3 depends within the vessel, the smaller lower end of the receptacle being closed.

Normally fitted within the mouth of the receptacle 3 is a hollow sheet metal float or buoy 5, embodying a cup-shaped section 6 having an outturned annular flange or rim 7, and a cap section 8 having its margin riveted or otherwise secured upon the rim 7. The walls of the float 5 are tapered or frusto-conical so as to fit snugly within the mouth portion of the receptacle 3 to provide a tight fitting closure for the receptacle to normally keep out the water, the rim 7 fitting snugly upon the shell and around the opening 2. The cap section 8 of the float 5 is preferably convexed or dome-shaped to better resist the water pressure to which the float is subjected when the vessel is submerged. The cap section 8 of the float has attached to the central portion thereof an eye bolt 9 which may be employed for the attachment of a cable or other device to the float when desired. The bottom of the float 5 is concaved or dished, and is provided with a central depending boss 10 having a threaded socket.

A vertical spindle or rod 11 is engaged centrally through the bottom of the receptacle 3 and projects axially within said receptacle, the upper end of the spindle 11 being threaded into the boss 10. The spindle 11 is slidable through a packing device 12 carried by the bottom of the receptacle

to prevent leakage, and the lower terminal of the spindle is slidable through a U-shaped bracket 13 having its ends attached to the bottom of the receptacle. The lower 5 end of the spindle 11 has a handle 14, and the spindle is slidable through a cross bar 15 of the bracket 13, a hand wheel or nut 16 being threaded upon the spindle and bearing against the cross bar 15, whereby 10 the wheel 16 can be rotated for pulling the stem 11 downwardly to draw the float 5 tightly within the mouth portion of the receptacle 3 for providing a tight closure. The handle 14 is employed for unscrewing 15 the spindle 11 from the float, to liberate the float.

Attached to the bottom of the float 5 is an eye bolt or other attaching element 17, to which is attached the upper end of a light 20 cable 18, and a heavy or strong cable 20 has its lower end attached to one or more eye bolts 19 secured to the bottom or lower end of the receptacle 3. The adjacent ends of the cables 19-20 are connected by a coupling 21 which embodies a tapered or conical shell 22 having an aperture 23 at its apex or smaller end through which the lower end of the cable 18 extends, the cable 18 being doubled or looped, as at 24, within the shell 25 22. The larger end or base of the shell 22 has an aperture 25 through which the upper 30 end of the cable 20 projects, said cable 20 being looped or doubled, as at 26, within the shell 22. The shell 22 is filled with lead or 35 equivalent material, as at 27, whereby the ends of the cables 18-20 are securely anchored within the shell 22, for attaching the cables together. The apex or smaller end of the shell 22 is uppermost, and the base or 40 larger end is provided with a depending annular or marginal rib 28 for the engagement of the grapnel with the coupling 21.

The grapnel embodies a sleeve 29 adapted to be slid downwardly along the cable 18, 45 and a plurality of arms or shanks 31 are pivoted at their upper ends to the sleeve 29, and the lower or free ends of the arms 31 having inwardly projecting hooks 32. The said hooks have outstanding lugs 33 at their 50 heels, for supporting a ring 34. The sleeve 29 is of tapered form, and has attached thereto, a hoisting or lifting cable 30.

The receptacle 3 is provided with a faucet or outlet valve 35 at its lower end, which 55 can be opened to determine whether there is water within the receptacle, or for draining the receptacle.

Ordinarily, the floats 5 are held tightly within the receptacles 3 by means of the 60 spindles 11, to exclude water from the receptacles. In case of accident or injury, should the vessel sink, the spindles 11 are unscrewed by members of the crew or passengers, to detach the floats 5, and said floats will immediately rise to the surface of the water, pulling

upward therewith, the cables 18-20. If the water does not pass under the floats, due to the tight fit between the floats and receptacles, the loosened spindles 11 can be employed for jarring the floats loose, or for 70 ejecting the floats, so that they will rise to the surface of the water. The floats will therefore serve to locate the sunken vessel, in order that it may be salvaged quickly and conveniently. To raise the vessel, a grapnel 75 is guided down each of the cables 18, the sleeve 29 of the grapnel being placed upon the said cable 18, and the grapnel is let down by the cable 30. When the grapnel reaches the coupling 21, the hooks 32 are separated by the coupling 21, and then when the hooks 32 reach the lower end of the coupling 21, they swing inwardly under the rib 28 to get a good hold on the coupling 21. The ring 34 is then dropped, the same being guided 80 along the cables 18 and 30, and the ring 34 slides downwardly over the sleeve 29 and arms 31, to hold the hooks 32 fast to the coupling 21, the ring 34 being supported by the lugs 33. The cable 30 can then be raised 85 for raising the vessel, it being noted that the cable 30 is connected by the coupling 21 to the heavy cable 20. The heavy cable 20 need only be of short length, while the cable 18 is light since it need only be strong enough to 90 raise the cable 20 and coupling 21. It makes no difference whether the vessel is in upright position or is turned over on one side, the cables 20 will be lifted by the cables 19 to raise the couplings 21 above the vessel, so 95 that the grapsnels can be properly engaged with the couplings 21. The person releasing one of the floats can readily determine whether the same has left the receptacle, by simply opening the faucet 35, and if water 100 flows through the faucet, this is evidence of the fact that the float has left the receptacle in order that water can enter the receptacle. It is evident, that ordinarily, the cables 18-20 are coiled up within the receptacle 3, the cables 18 being sufficiently long to let 105 the floats rise to the surface of the water, and if the cables 20 are not pulled out of the receptacle 3 by the cables 18, the cables 18 can be pulled upwardly by the members 110 of the salvaging vessel for raising the couplings 21 so that the grapsnels can be engaged 115 therewith.

The pintles 11 need only be used when the devices are employed on a submarine vessel. 120 since with a separate vessel, the floats will ordinarily be above the water so that they have no tendency to be dislodged accidentally.

Having thus described the invention, 125 what is claimed as new is:

In an apparatus of the character described, a receptacle adapted to be carried by a vessel, a float fitting within the mouth of the receptacle, a U-shaped bracket having its 130

ends attached to the bottom of the receptacle and having a cross bar therein, a spindle slideable through the bottom of the receptacle and having one end threadedly engaging the float, the spindle having a handle at its other end, the spindle being slideable through said bracket, and a nut threaded upon the spindle and bearing against said cross bar.

In testimony that we claim the foregoing 10 as our own, we have hereto affixed our signatures in the presence of two witnesses.

JOHN F. NEAL.
DOREL NEAL.
